UNITED STATES PATENT OFFICE.

CHARLES HENRY ROSENTHAL, OF CINCINNATI, OHIO, ASSIGNOR OF ONE-
THIRD TO LOUIS W. WYLER.

TOOL FOR REMOVING SHELL-CROWNS FROM TEETH.

SPECIFICATION forming part of Letters Patent No. 403,293, dated May 14, 1889.

Application filed March 18, 1889. Serial No. 303,668. (No model.)

To all whom it may concern:

Be it known that I, CHARLES HENRY ROSENTHAL, a citizen of the United States, residing in Cincinnati, Hamilton county, Ohio, have

5 invented certain new and useful Improvements in Devices for Removing Shell-Crowns from Teeth, of which the following is a specification, reference being had to the accompanying drawings, forming a part hereof, in
10 which—

Figure 1 is my invention. Fig. 2 is a vertical section through the center of all the parts, enlarged, with the top of the handle broken away. Fig. 3 is a detail of the clamp. Fig. 4 is a detail of the elongated nut, having a flange on the lower edge. Fig. 5 is a shell-crown, which I do not claim as part of my invention, but show it for illustration.

15 Similar letters of reference throughout the 20 several figures denote the same parts.

In the drawings, H is the handle, having on one end a screw-threaded shaft, S, adapted to work in the elongated screw-threaded nut N, having a flange on its lower end.

25 C is the clamp, having a hole in the center of its top adapted to fit loosely about the nut N and having its sides bent at right angles to the top and the lower end of the sides bent in at right angles to the same to form flanges, 30 as seen at c, adapted to fit under and engage with the lower edge of a shell-crown, O, having a hole in the center of its top adapted to allow the end of the screw-threaded shaft S to pass through on either side of a tooth.

35 Operation: I operate my invention by passing the screw-threaded nut N through the hole in the top of the clamp C, pass the screw-threaded shaft S through the nut N until the end of the shaft S is passed through the hole 40 in the top of the shell-crown O and rests upon the tooth, the sides of the clamp C having been passed down the sides of the shell-crown O until the flange c springs into place under the edges of the shell-crown and on either 45 side of the tooth. By turning the handle H the nut N passes through the hole in clamp C, (about which said clamp is loosely journaled,) till the flange on the nut N comes in contact with the clamp C, and by continuing to turn 50 the handle H the nut N, pressing against the

clamp C, gradually raises the same, and the shell-crown O, about which the clamp is placed and engaged with, is readily removed from the tooth.

In making shell-crowns for teeth it is necessary to put them on and take them off many times in order to fit them to the tooth and gum. Before the making of my improvement dentists have labored at great disadvantage, in not being able to make a close-fitting shell-crown, for the reason that it could not be readily removed. The object of my invention is to overcome this difficulty. I loosely journal the clamp C on the nut N for the purpose of enabling the operator to change the handle 55 from a perpendicular to almost any angle, and pressure can be had on a tooth in any part of the mouth. In the drawings I show a handle of the ordinary tools of dentists; but, if necessary, the handle can be short and perforated, 60 having holes cut at right angles adapted to receive a lever for the purpose of turning the shaft S in the nut N, or the shaft S can be attached to a flexible shaft and turned in that manner, so that a shell-crown can be readily 65 removed from any part of the mouth.

I only show one form of constructing the clamp C; but when necessary for different-shaped teeth I change the form of the lower part of the clamp to conform to the shape of 70 the tooth, or I make the lower end of the clamp pointed with the flanges, as occasion may require.

Having thus fully described my invention, what I claim as new therein, and desire to obtain by Letters Patent, is—

In a device for removing shell-crowns from teeth, the elongated internal screw-threaded nut N, adapted to receive a screw-thread shaft, S, in combination with the clamp C, 80 loosely journaled on the nut N, having the flanges c, substantially as shown and described.

The foregoing specification of my invention signed by me this 9th day of March, A. D. 95. 85
1889.

CHARLES HENRY ROSENTHAL.
